STEERING CONTROL MEANS FOR INBOARD-OUTBOARD DRIVES

Daniel F. McCormick, Fond du Lac, Wis., assignor to Kiekhaefer Corporation, Cedarburg, Wis., a corporation of Delaware

Filed July 13, 1962, Ser. No. 209,674
6 Claims. (Cl. 115—35)

This invention relates to the steering control means for an inboard-outboard drive for watercraft.

The outboard drive unit of inboard-outboard drives commonly pivot on a generally vertical swivel axis for steering. Generally the steering is controlled from a remote location in the watercraft by means of a flexible push-pull cable actuated by a steering wheel or the like. In inboard-outboard drives wherein the outboard drive unit is invertable by rotation in the transverse vertical plane for beaching or repair, it is generally necessary to first make a disconnection between the drive unit and the steering means prior to inversion. Such a disconnection not only takes time, but also may require tools which may or may not be handy, and may involve certain other difficulties. It is generally an object of this invention to provide a steering arrangement for outboard drive units wherein a disconnection of the steering mechanism is unnecessary when it is desired to invert the drive unit by rotation in a transverse vertical plane.

According to this invention, the outboard drive or propulsion unit is pivotally supported by a support housing structure on a generally vertical axis for steering. The support housing structure includes a forwardly extending cylindrical portion which is adapted to be received within an opening in the transom and is releasably secured therein. Means are provided to rotate the support housing structure within the opening to rotate the drive unit in a transverse vertical plane to invert the unit when desired. A steering arm is disposed within the cylindrical portion of the support structure and projects inboard of the watercraft. The arm is pivotal on a generally vertical axis to actuate a linkage arrangement connected to the outboard drive unit to effect steering and is also rotatable with the drive unit and support housing in a transverse vertical plane. A flexible push-pull cable operated by a steering wheel or the like from a remote location in the watercraft is adapted to actuate a telescoping mechanism. One element of the telescoping mechanism comprises a rigid tubular extension of the push-pull cable casing and is universally supported from the transom of the watercraft. The other element of the telescoping mechanism comprises a rigid tubular member fastened to the push-pull cable core wire and is universally connected to the free end of the steering arm. Relative slidable movement between the elements as effected by the push-pull cable actuates the steering arm to effect steering control of the propulsion unit. Upon rotation of the steering arm with the support housing and propulsion unit in a transverse vertical plane when desired, the core wire is movable within the push-pull cable to accommodate relative movement between the elements of the telescoping mechanism making disconnection of the steering mechanism unnecessary.

The drawings furnished herewith illustrate the best mode for carrying out the invention as presently contemplated and set forth hereinafter.

In the drawings:

FIGURE 1 is a perspective view of the dirigible outboard drive or propulsion unit of an inboard-outboard drive shown mounted on the transom of a watercraft;

FIG. 2 is an enlarged partial side elevation of an inboard-outboard drive with parts broken away and sectioned to show the steering mechanism for the outboard drive unit;

2

FIG. 3 is a rear elevational view of the propulsion unit of an inboard-outboard drive showing the unit in the drive position, and in phantom showing the unit in one position of its path in the transverse vertical plane and in its fully inverted position;

FIG. 4 is a plan view of a watercraft having an inboard-outboard drive showing generally the arrangement for remotely actuating the steering mechanism for the drive unit, and

FIG. 5 is a view taken generally on line 5—5 of FIG. 4 and in phantom lines illustrates the effect inversion of the drive unit imparts on the steering arrangement of the unit.

Referring to the drawings, the inboard-outboard drive includes a propulsion unit 1 suspended from the transom 2 of a partially shown boat or other watercraft 3. The propulsion unit 1 includes a propeller 4 which is driven by the engine 5 mounted inboard of the boat to be propelled.

The propeller 4 of the propulsion unit 1 is carried by the generally horizontal propeller shaft 6 which is driven through beveled gears 7 and 8 by the generally vertical drive shaft 9 rotatably supported within housing 10 of the propulsion unit. A pair of vertically spaced beveled gears 11 and 12, one of which is a forward gear and the other a reverse gear, are mounted in suitable bearings and are freely rotatable on the upper end of shaft 9. The drive gear 13 the axis of which is disposed generally horizontally, drivingly engages the beveled gears 11 and 12 and causes the gears to rotate in opposed directions. The clutch element 14 disposed between gears 11 and 12 is carried by shaft 19 and is slidable axially thereon to selectively engage gears 11 and 12 to complete the drive connection between the drive gear 13 and shaft 9. The clutch element 14 also has an intermediate "neutral" position between gears 11 and 12 in which case the propeller 4 is inoperative.

The drive gear 13 is driven by engine 5 through the generally horizontal drive connection including axially spaced and aligned shaft members 15 and 16 which are connected by the double universal joint 17 disposed generally at the intersection of the generally transverse vertical and horizontal planes respectively containing the swivel and tilt axes of the propulsion unit.

The suspension means for the propulsion unit 1 includes a housing member 18 comprising a forwardly extending cylindrical steering lever housing 19 and a rearwardly extending bell-shaped housing 20 which are separated by a partition wall 21 having an opening 22 centrally thereof through which the horizontal drive shaft 16 extends. The cylindrical steering lever housing 19 is slidably and rotatably received within the stepped transom opening 23 formed in the telescopingly related outer plate 24 and inner plate 25 secured to the transom 2 of the watercraft. Housing 19 extends through the opening 23 and into the watercraft and the nut member 26 is threaded on the forward end thereof and is adapted to draw and rigidly secure or clamp housing member 18 into its forwardmost normal running position.

The housing 10 of the propulsion or drive unit 1 is pivotally supported from an intermediate gimbal ring member 27 on a generally transverse horizontal axis indicated at 28 to provide for tilt movements of the drive unit in a generally vertical plane. The gimbal ring member 27 is in turn pivotally supported from housing member 18 on a generally vertical axis provided by the vertically spaced and aligned shaft portions 29 and 30 to provide for steering movement of the propulsion unit in a generally horizontal plane.

Steering control movement of the gimbal ring member 27 together with the drive unit 1 is effected by the lever arm 31 which projects from the steering lever housing 19 into the watercraft. Arm 31 is fixedly secured on the

upper end of the generally vertical shaft 32 which is rotatably supported in the boss 33 projecting forwardly from the partition wall 21 offset outwardly from opening 22 within lever housing 19. The lower end of shaft 32 extends into the chamber 34 beneath the drive shaft 16 in the lower portion of housing 19 and carries the crank arm 35 within the chamber. A linkage member 36 extends through opening 37 in the partition wall 21 between the lever housing 19 and the bell-shaped housing 20 and is pivotally connected to the gimbal ring member 27 and the crank arm 35 respectively to complete the steering connection from lever arm 31.

As shown generally in FIGS. 3 and 5, the drive unit 1 is also rotatable for movement in a generally transverse vertical plane to an inverted position for beaching or repair. The described inversion of the drive unit 1 is effected by counterclockwise rotation of housing member 18, as viewed in FIG. 5, within transom opening 23 by means not forming a part of the present invention. As shown in FIG. 5, the steering lever arm 31 is displaced substantially 180° as the arm rotates concentrically about shaft 16 together with housing member 18 to effect drive unit inversion.

The steering means not requiring a disconnection from the drive unit during inversion of the unit includes the telescopingly related tubular members 38 and 39. Tubular member 38 constitutes an extension of the core wire 40 of steering control cable 41 and the free end thereof is pivotally secured within yoke member 42 on the steering lever arm 31. The yoke member 42 is pivotally secured to arm 31 on an axis generally normal to the pivot axis of tubular member 38 so that the end of the tubular member is universally connected to the steering lever arm 31.

The tubular member 38 is slidable within the tubular member 39 which constitutes an extension of the casing 43 of the steering cable 41. The tubular member 39 is pivotally secured within the yoke bracket 44 mounted on the inner transom plate extension 45 on the side of shaft 16 about which the steering arm 31 rotates during inversion of the drive unit. Yoke bracket 44 is pivotally secured to the transom plate extension 45 on an axis generally normal to the pivot axis of member 39 within bracket 44 to provide a universal mounting of member 39 relative to the transom.

Steering control for drive unit 1 is provided by actuation of the core wire 40 of cable 41 to move tubular member 38 axially relative to member 39 and thereby actuate the steering lever arm 31 correspondingly.

Steering movement of the lever arm 31 is controlled through cable 41 from a remote location within the watercraft 3 by a steering wheel 46 or the like which rotates the steering shaft 47 in the desired manner. The shaft 47 carries the gear 48 which meshes with a rack 49 slidably disposed in the gear housing 50. The steering cable 41 extends to the housing 50 and a cable coupler element 51 fixedly secures the cable casing 43 relative to the housing. The cable core wire 40 extends through the coupler element 51 and is secured to the rack 49. Thus, movements of rack 49 as effected by operation of the steering wheel 46 actuates the cable core wire 40 and thereby controls the steering movement of lever arm 31.

When the drive unit 1 is rotated in its generally transverse vertical path to effect inversion of the unit, the lever arm 31 is correspondingly rotated on the opposite side of shaft 16 and also assumes an inverted position. The yoke member 42 and yoke bracket 44 connected to the lever arm 31 and transom plate 45 respectively, are adapted to pivot relative to the corresponding member to accommodate the movement of the arm into the inverted position. Inversion of arm 31 also produces a constantly changing effective length of the telescoping mechanism as generally shown in FIG. 5. To accommodate the changes in effective length of the telescoping mechanism, the cable core wire 40 is free to move within

casing 43 and such movement is simply fed back or reflected in corresponding movements of steering wheel 46. The invention therefore provides steering control means for an outboard drive unit which is fully capable of accommodating an inversion of the drive unit in a transverse vertical path without a disconnection from the unit.

Various modes of carrying out the invention are contemplated as being within the scope of the following claims particularly pointing out and distinctly claiming the subject matter which is regarded as the invention.

I claim:

1. In combination with an outboard propulsion unit for driving a watercraft, said propulsion unit being pivotally carried on a generally vertical axis for steering by support means mounted on the transom of the watercraft and being rotatable in a transverse vertical plane with said support means to an inverted position; a steering arm for the propulsion unit carried by the support means and being rotatable therewith; and means for actuating said arm from a remote location in the watercraft to effect steering control of the propulsion unit and comprising a pair of telescopingly related elements, means universally connecting one end of one of said elements to the steering arm, means universally connecting the other element to the transom of the watercraft, whereby telescoping movements of said elements effects pivotal steering movement of said arm, and push-pull means to actuate the telescoping elements; said means for actuating said steering arm being freely movable by said arm to accommodate movement of the arm during rotation of the propulsion unit in the transverse vertical plane.

2. In combination with an outboard propulsion unit for driving a watercraft, said propulsion unit being pivotally carried on a generally vertical axis for steering by support means mounted on the transom of the watercraft and being rotatable in a transverse vertical plane with said support means to an inverted position; a steering arm for the propulsion unit pivotally carried by the support means and being rotatable therewith; and means for actuating said arm from a remote location in the watercraft to effect steering control of the propulsion unit and comprising a pair of telescopingly related elements, means universally connecting one end of one of said elements to the steering arm, means universally connecting the other element to the transom of the watercraft, whereby telescoping movements of said elements effects pivotal steering movement of said arm, a rack member reciprocally disposed within a housing at a location in the watercraft remote from the propulsion unit, a gear in meshing engagement with the rack member, means to rotate the gear, flexible push-pull means comprising a casing and a movable core wire therewithin, means connecting the ends of the casing of said push-pull means to the telescoping element connected to the transom and the rack member housing respectively, and means connecting the ends of the movable core wire of the push-pull means to the telescoping element connected to the steering arm and the rack member respectively, said gear being rotatable to correspondingly actuate the core wire of the push-pull means and thereby provide for steering control of the propulsion unit, and said gear and the means for rotating same being freely rotatable by movement of said core wire as effected by the steering arm during rotation of the propulsion unit in a transverse vertical plane to an inverted position.

3. In a combination with an outboard propulsion unit for driving a watercraft, said propulsion unit being pivotally carried on a generally vertical axis for steering by support means mounted on the transom of the watercraft and being rotatable in a transverse vertical plane with said support means to an inverted position; a steering arm for the propulsion unit pivotally carried by the support means and being rotatable therewith; and means for actuating said arm from a remote location in the watercraft to effect steering control of the propulsion unit and

comprising a pair of telescopingly related elements, means universally connecting one end of one of said elements to the steering arm, means universally connecting the other element to the transom of the watercraft, whereby telescoping movements of said elements effects pivotal steering movement of said arm, flexible push-pull means comprising a casing and a core wire therewithin, means connecting the casing of said push-pull means to the telescoping element connected to the transom, means connecting the core wire of the push-pull means to the telescoping element connected to the steering arm, and means to actuate the push-pull means to thereby actuate the telescoping elements; said means for actuating said steering arm being freely movable by said arm to accommodate movement of the arm during rotation of the propulsion unit in the transverse vertical plane to an inverted position.

4. In a combination with an outboard propulsion unit for driving a watercraft, said propulsion unit being pivotally carried on a generally vertical axis for steering by support means mounted on the transom and being driven by a generally horizontal shaft extending through said support means and being rotatable in a transverse vertical plane with said support means and relative to said shaft to a generally inverted position, a steering arm for the propulsion unit pivotally carried by the support means and extending to the inside of the watercraft in offset relation from said shaft and being rotatable with the support means relative to said shaft with the arm moving on a given side of the shaft, and means to actuate said arm for steering control of the propulsion unit, said means to actuate the steering arm being universally mounted on the transom on said given side of the shaft and being adapted to accommodate movement of the arm during rotation of the propulsion unit in the transverse vertical plane to an inverted position.

5. The invention of claim 4 wherein the means to actuate the steering arm includes a pair of telescopingly related elements, an end of one of said elements being universally connected to the steering arm and the other element being universally mounted on the transom.

6. In combination with an outboard propulsion unit for driving a watercraft; said propulsion unit being pivotally carried on a generally vertical axis for steering by support means mounted on the transom of the watercraft and being rotatable in a transverse vertical plane with said support means; means for pivoting the propulsion unit for steering control of the unit and extending through the support means and into the watercraft; said steering means being rotatable with said support means and propulsion unit; and means for actuating said steering means from a remote location in the watercraft and comprising a pair of telescopingly related elements, means universally connecting one end of one of said elements to the steering means, means universally connecting the other element to the transom of the watercraft, whereby telescoping movements of said elements effects steering control movement of said steering means, and push-pull means to actuate the telescoping elements; said means for actuating said steering means being freely movable by said steering means to accommodate movement of the steering means during rotation of the propulsion unit in the transverse vertical plane.
